[57] CLAIM

The ornamental design for an outdoor shower fixture, as shown and described.

DESCRIPTION

FIG. 1 is a top, front, right side perspective view of an outdoor shower fixture showing my new design;

FIG. 2 is a front elevation view thereof;

FIG. 3 is a right side elevational view thereof, the left side
being a mirror image thereof;

FIG. 4 is a top plan view thereof; and,

FIG. 5 is a bottom plan view thereof.

The rear view is plain and includes no ornamental features.
The broken lines showing a shower head, a control valve and a support wall are for illustrative purposes only and form no part of the claimed design.
